UNITED STATES PATENT OFFICE.

KENJI HORIHATA, OF WHITE PLAINS, NEW YORK.

WINDOW CLEANER.

Application filed August 18, 1926. Serial No. 130,021.

My invention relates to a window cleaner of the type having a pair of cleaning heads adapted to be positioned at opposite sides of a window pane. The general object of 5 my present invention is to provide a window cleaner of the indicated type improved in various particulars whereby to promote convenience and effectiveness in the use of the cleaner.

10 The nature of my invention and its distinguishing features and advantages will clearly appear as the description proceeds.

Reference is to be had to the accompanying drawings forming part of this specification, it being understood that the drawings 15 are merely illustrative of one example of the invention.

Figure 1 is a perspective view of a window cleaner embodying my present invention showing the same disposed for use on a 20 window sash shown in part.

Figure 2 is a vertical section on an enlarged scale of the upper portion of the window cleaner.

25 Figure 3 is a vertical section of the attachment at the upper end of one of the handle members.

Figure 4 is a cross section on the line 4—4, Figure 2.

30 Figure 5 is a fragmentary plan view showing a portion of one of the fabric strips.

In carrying out my invention in accordance with the illustrated example two handle 35 members 10 are provided joined by a cross bar 11 adapted to be grasped by the user of the device. Two cleaning heads are provided designated generally by the numeral 12.

Bails 14, 114 are pivotally secured to the respective heads 12, said bails having pins 40 13, 113 secured to the respective handles 10, the pins 13 being inserted directly in the end of one handle member 10, and the other pins 113 being inserted in rolled edges 115 of a semi-circular element 15 on the other handle

45 member 10. Each head 12 is adapted to receive cleaning fabric 17 wound on shafts 16 on the bails 14, 114, and said fabric runs from said shafts 16 and are wrapped about an adjacent head 12. Those portions of the

50 fabric strip 17 positioned at the ends of the heads 12 have water repellent zones 117 to confine the wet portion of the fabric substantially to the rubbing faces of the heads 12.

At one face of each head 12 the said head 55 carries a sponge rubber 27 or equivalent absorbent material in the form of a pad. A

fabric pad 19 is disposed at the opposite sides of each head 12. Separating the two pads 18 and 19 is a partition or backing plate 20, the ends of which are bent back and forth to provide two clamps 21 between which the pad 18 is held resiliently and at the opposite side of the head clamps 121 to hold the pad 19. The numeral 22 indicates an ordinary pin fastening fabric 17 at an end of each head to prevent unwinding of the fabric strip.

The element 15 is semi-circular in cross section, see Figure 4, and is pivoted as at 23 remote from an end of one of the handle 70 members 10 to lie against said handle member and to swing toward and from the same which will be clear from a comparison of Figures 2 and 3. A spring 24 is interposed between the element 15 and the handle member 10 to which it is pivoted as shown clearly in Figures 2 and 3, and tends to throw said element 15 outwardly at an angle to the handle member 10. The element 15 is locked against movement to its outer position by spring 24 through the medium of a suitable latch means which advantageously takes the form of the strip 25 projecting laterally through a hole 26 in element 15 so that the teeth of said strip 25 will engage said element 15 to hold it close to handle member 10. 75

The clamps 21 are adapted to receive scraper blades, preferably safety razor blades. When these are to be used the fabric strip 15 is rolled on to shaft or roller 16 90 that the blade may be employed for scraping the window pane.

I would state furthermore, that while the illustrated example constitutes a practical embodiment of my invention, I do not limit myself strictly to the exact details herein illustrated since, manifestly, the same can be considerably varied without departure from the spirit of the invention as defined in the appended claims. 95

100 What I claim is:

1. A window cleaner including handle members, a cross bar connecting said handles, a cleaning head, a second cleaning head, a yoke carrying said first head, a yoke carrying said second cleaning head, an element pivoted adjacent to the other handle member and carrying said second yoke, latch means to hold the pivoted element adjacent the handle member to which it is pivoted, said latch means being mounted on said last mentioned handle member, rollers turnably 105 110

mounted in said yokes and fabric strips wound on said rollers and wrapped about said heads.

2. In a window cleaner, handle members, 5 a cross bar connecting said handles, heads turnably mounted on said handle members and presenting opposite faces, pads carried

by said heads at the opposite faces and a fabric strip wrapped about each head to furnish rubbing faces thereon, the said strip having spaced portions treated with water repellent material embodied in the strip 10 adapted to overlie the edges of the head.

KENJI HORIHATA.
